UNITED STATES PATENT OFFICE.

SIDNEY GEORGE GRANDJEAN AND JESSE JOHN DARCEY, OF BRAITHWAITE,
LOUISIANA.

ILLUMINATED AUTOMOBILE SIGNAL.

Application filed July 2, 1921. Serial No. 482,241.

To all whom it may concern:

Be it known that we, SIDNEY GEORGE GRANDJEAN and JESSE JOHN DARCEY, citizens of the United States, residing at Braithwaite, in the parish of Plaquemine and State of Louisiana, respectively, have invented new and useful Improvements in Illuminated Automobile Signals, of which the following is a specification.

Our present invention has for its object the provision of a simple, compact and reliable automobile signal through the medium of which the driver of an automobile is enabled to communicate his intentions to persons at the back of the car as well as to persons in front of the car he is driving.

To the attainment of the foregoing, the invention consists in the improvement as hereinafter described and definitely claimed.

In the accompanying drawings, forming part of this specification:—

Figure 1 is an elevation showing the rear side of the signal constituting the best practical embodiment of our invention that we have as yet devised.

Figure 2 is a vertical section taken in a plane parallel to Figure 1.

Figure 3 is a vertical section taken transversely of Figure 2.

Figure 4 is a horizontal section on the line 4—4 of Figure 2.

Figure 5 is a detail perspective showing a portion of the panel hereinafter referred to in detail.

Similar numerals of reference designate corresponding parts in all of the views of the drawings.

Among other elements our novel signal comprises a casing body 1, preferably of sheet metal and normally closed through the medium of a door 2, hinged at 3 and designed to be retained detachably in closed position through the medium of a latch 4, Figure 2. Formed by stenciling in the front and rear walls of the casing body 1, Figure 4, are the words Slow, Right, Left, Back and Stop, the said words being each arranged in a horizontal line, and the said lines being arranged in a vertical series as clearly shown in Figure 1. Arranged within the casing body 1 and immediately against the side walls of the casing body are panes of glass 5 and 6, the glass 5 at the rear being preferably colored red and the glass 6 at the front 55 being preferably colored green.

In addition to the casing body 1 and its door 2, the signal comprises a removable panel 7, and a plurality of horizontally disposed partitions 8, the said partitions 8 being preferably of sheet metal and fixedly joined in appropriate manner to the wall 9 of the casing body remote from the door 2. The said partitions 8 are also approximately joined to upright rods 10 of wire which extend between and are connected to the upper and lower end walls of the casing body 1, with the result that the partitions 8 are strongly maintained in spaced relation in the casing body. As best shown in Figure 3 each of the partitions 8 is provided with rear and forward flanges 11 which depend from the partitions and are concavo-convex in vertical section. These flanges 11 serve to receive and hold pads 12 of wicking, rope or the like; the said pads 12 being interposed between the panes of glass 5 and 6 and the flange 11 and being adapted to serve the important purposes of preventing rattling or breaking of the panes of glass, and precluding the passage of light from one compartment 13 of the signal to an adjoining compartment or compartments.

The panel 7 is preferably of sheet metal and is snugly though removably arranged in the casing body 1 between the side walls and also between the top and bottom walls thereof as best shown in Figures 2 and 4. The said panel 7 is equipped with spring clips 14, the function of which is to detachably connect it to the ends of the partitions 8 adjacent to the door 2. It will thus be seen that the panel 7 is strongly maintained in proper working position in the casing body 1 and yet is susceptible of ready removal from said casing body 1 when occasion demands. At intervals in its length the panel 7 is provided with apertures 15 to snugly receive sockets 16 of incandescent electric lamps 17 of which there is one employed to each compartment 13. Manifestly when the panel 7 is removed from the casing body 1, the lamps 17 may be quickly and easily disassociated from their sockets 16 and replaced with fresh lamps.

We contemplate controlling our novel signal through the medium of a five gang switch appropriately mounted on or attached to the steering post of an automobile, and a five wire cable indicated by 18 in Figure 2 from the said switch through the

- bottom of the casing body 1 to the several lamp sockets. We also contemplate the employment of an arrangement that includes the grounding of the metallic casing body 1 to the car to make the return and complete the circuit. This electric arrangement, however, is not of our invention, and we have therefore deemed it unnecessary to illustrate and specifically describe the same.
- 10 In order to intensify the light within the compartments 13 we prefer to make the insides of the compartments of reflecting metal. This, however, is not of the essence of our invention.
- 15 It will be apparent from the foregoing, that by manipulating the switch alluded to, the operator of an automobile may illuminate any one of the compartments 13 whereupon the illuminated word in the rear and forward walls of the casing body 1 will convey to persons in rear and in front of a car, the intention of the driver of the car. It will also be apparent that the device is simple and inexpensive in construction and
- 20 25 is well adapted to withstand the usage to which automobile signals are ordinarily subjected.
- We have entered into a detailed description of the construction and relative arrangement of parts embraced in the present and preferred embodiment of our invention in order to impart a full, clear and exact understanding of the said embodiment. We do not desire, however, to be understood as confining ourselves to the said specific construction and relative arrangement of parts inasmuch as in the future practice of the invention various changes and modifications

may be made such as fall within the scope of our invention as defined in our appended 40 claim.

Having described our invention, what we claim and desire to secure by Letters-Patent, is:—

An automobile signal comprising a casing 45 body having a wall and signal openings therein, a door complementary to said body, a pane of glass within the casing body and against the wall in which the signal openings are provided, partitions in the casing 50 body in spaced relation to each other and having lateral edge flanges of concavo-convex form in section with their concave sides opposed to said glass, said partitions forming compartments one to each signal opening, packing strips held in said flanges against the pane of glass to prevent rattling and the passage of light, means interposed between opposite walls of the casing body and extending at right angles to the partitions and engaging the partitions to assist in maintaining the latter in position, a removable panel disposed in the casing body in spaced relation to said door and having means detachably engaging the ends of the 60 partitions to hold the panel to the partitions and also having apertures, and incandescent lamp sockets arranged in the said apertures of the panel and adapted to carry bulbs one for each compartment formed by the said 65 partitions.

In testimony whereof, we affix our signatures.

SIDNEY GEORGE GRANDJEAN.
JESSE JOHN DARCEY.
